UNITED STATES PATENT OFFICE.

TAUBE DAVIS, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed August 11, 1926. Serial No. 18,694. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by having a jumper or tunic with an ornamental pointed front section and an ornamental yoke near the upper part of the back having a V-shaped central section. The dress is further distinguished by the ornamental arrangement of box plaits with

pointed ornamental stitching spaced an appreciable distance from the lower edge of the skirt and co-operating with the ornamental neck member for presenting a uniform appearance throughout the dress. Arranged near the lower edge of the tunic is a belt having an ornamental chain section in the center of the front.

Figure 1 is a front view of a dress, showing my new design.

Figure 2 is a rear view of the dress shown in Figure 1.

I claim:

The ornamental design for a dress, substantially as shown and described.

TAUBE DAVIS.
